UNITED STATES PATENT OFFICE.

ROBERT W. HAWES, OF BRUNSWICK, GEORGIA.

SCAFFOLD.

1,312,398.

Specification of Letters Patent. Patented Aug. 5, 1919.

Application filed November 12, 1918. Serial No. 262,191.

To all whom it may concern:

Be it known that I, ROBERT W. HAWES, a citizen of the United States, resident of Brunswick, in the county of Glynn and State of Georgia, have made a certain new and useful Invention in Scaffolds; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is an end view of the invention, as applied.

Fig. 2 is a front view of the same with parts broken away.

Fig. 3 is a plan view of one platform section, showing the standards in section.

Fig. 4 is a detail perspective view of a portion of a platform section.

Fig. 5 is a detail fragmentary plan view of a platform section with the floor boards removed and the post in section.

Fig. 6 is an end view of a platform section.

The invention has relation to scaffolding, adapted mainly for use in the building of wooden ships, having for its object to facilitate the transfer of the heavy wooden side timbers or weatherboarding longitudinally of the ship's side, and to facilitate the handling or application of said timbers to the framing of the ship. Other objects and advantages will hereinafter appear.

The invention consists in the novel construction and combinations of parts, as hereinafter set forth.

In the accompanying drawings illustrating the invention, the numeral 2 designates the frame or skeleton of a ship, including ribs 3, and 4 are the side timbers or weather-

boarding.

5 Adjacent to the side of the ship is arranged an upright supporting or studding frame 5, including uprights or posts 6, spaced apart by suitable intervals and suitably braced or supported in vertical position, as by transverse members 7, connected to the ship's framing.

The posts 6 are each provided with a vertical series of outwardly and upwardly extending hooks 8, providing open-end seats 9 between the same and the adjacent faces 55 of the posts.

The platform members upon which the side timbers are transferred and upon which the workmen stand and move in applying these timbers to the ribs of the ship are designated 10, being made in sections, abutted end to end, and each section preferably thirty feet long by five feet wide, by five feet eight inches in height. Each platform section consists of uprights 11, spaced apart by distances equal to the distances separating the posts 6 of the studding or supporting frame, and connected upon the outside by three beams or stringers 12, 13, and 14 located respectively at the top, bottom and middle of each section, a fourth beam or stringer 15, corresponding in height and dimensions with the middle stringer 14 being connected and braced to the back frame of each section by transverse 70 horizontal beams 16 mortised at their ends at 17 to the beams 14 and 15, and having a notch joint 18, with the post 11. The floor boards 19 of the platform sections are nailed to the transverse pieces 16, and have their 80 top surfaces substantially upon the same level as those of the stringers 14 and 15, the latter being located at the sides of the platform proper formed by the floor boards. The platforms of the sections 10 85 are braced to the back frames of the sections by diagonal or strut braces 20, nailed along their rear vertical margins to the posts 11; having horizontal extensions at 21 beneath the stringers 15, and upper ex-

90 tensions 22 between the stringers 14 and 15 to the floor boards, said upper extensions being nailed to the transverse pieces 16. Other transverse braces for the stringers 14 and 15 are shown at 23.

The upper and lower stringers 12 and 13 are usually two by eight inches in cross section, the center beams or stringers 14 and 15 at the sides of the platforms proper being two by ten inches.

100 The bottom faces of the lower and center stringers 13 and 14 are spaced apart by

- two feet six inches, and the bottom faces of the top and center stringers are similarly spaced apart. The hooks 8 in vertical series are also arranged horizontally in series, 5 each horizontal series engaging the upper and lower and center stringers, the latter fitting closely within the open-end seats 9 of the hooks, being let down therein from above by block and tackle gear. The 10 horizontal series of hooks 8 are therefore arranged at equal distances apart vertically to correspond with the equal distances separating the aforesaid upper, lower and central stringers, it being designed that 15 when the work upon the side of the ship is finished at that part of the ship related to the platform sections at one elevation, that these sections shall be lifted by the block and tackle gear from engagement with 20 the hooks 8 and raised or lowered to new position with relation to the side of the ship, being then engaged with other horizontal series of hooks 8 in the same way as first described, namely being let down in 25 the seats 9 from above.

The platforms of the sections are subjected to very heavy loads, the side timbers of ships being large and weighty, and it is designed by this invention to brace the 30 platforms against yielding under strain by extension of the back frames of the sections below the platforms proper and to insure the sections against tearing away from the posts 6, by extension of said frames above 35 the platforms, thus raising the angle of the point of support with relation to the free edge of the platform. The stringers, upper, lower and intermediate, of these back frames having engagement at intervals throughout 40 their lengths with the supporting hooks 8 of the studding, the horizontal distances separating the hooks and studding posts being equal to the horizontal distances separating the posts of the back frames of the platform 45 sections, whereby the supporting hooks are enabled to be located close to the posts 11, of said sections for better bracing or supporting effect. As the platform sections are raised or lowered to new positions with relation to the side of the ship, the stringers 12, 50 13 and 14 of the sections will fit interchangeably within the seats of the horizontal series of hooks 8, owing to the similar distances separating said stringers and separating said 55 hooks, these distances being equal as stated, thereby facilitating the re-location of the platform sections and making possible a greater number of relocations at lesser distances apart, since the platform may be 60 raised or lowered a distance equal to half the space separating the stringers 12 and 13.

The upper parts of the posts 11 and the upper stringers 12, engaging the hooks 8, not only afford a brace for the platform sections, as stated, but also act as a guard rail

or fence to prevent the workmen from falling over backwardly, this being important owing to the very considerable heights at which they work.

In order to build the platform sections 70 with the least weight, material and cost, it is found best to extend the longitudinal back timbers or stringers 12, 13, and 14, the stringer 15, and the floor boards of the platforms at each end of each section, a distance 75 equal to one half of the space separating the posts 11, of each platform section, (there being four such posts to the section). In this way, the platform sections being abutted end to end, the posts 11, of said sections or 80 of adjacent sections will always be equally spaced apart, as will also the transverse and strut braces.

The platform sections are provided with rollers 24, to facilitate the longitudinal 85 movement of the heavy ship timbers along the platforms.

I claim:—

1. In a scaffold, upright standards, outwardly and upwardly projecting hooks carried by said standards and including open-end seats between the same and the standards, and platform sections having each back frame provided with posts and with longitudinal stringers connecting said posts and 95 engaging said seats, said hooks being arranged in horizontal series, said series being spaced apart by distances equal to each other and equal to the distances separating said stringers, and said standards being spaced 100 apart by distances equal to the distances separating the posts of the platform sections, whereby the hooks of the standards are enabled to be located close to said posts.

2. In a scaffold, standards, outwardly and 105 upwardly projecting hooks carried by said standards and including open-end seats between the same and the standards, and platform sections having each a back frame provided with posts and with upper, lower and 110 middle stringers connecting said posts and engaging said seats, the platforms proper of said sections being located substantially on a level with the middle stringers, and the upper stringer and the upper portions of said 115 posts forming a guard or fence, said hooks being arranged in horizontal series, said series being spaced apart by distances equal to the distances separating said stringers, and said standards being spaced apart by distances equal to the 120 distances separating said posts.

3. In a scaffold, upright standards, outwardly and upwardly projecting hooks carried by said standards and including open-end seats between the same and the standards, and platform sections having each a back frame provided with posts and with longitudinal stringers connecting said posts and engaging said seats, said hooks being ar- 125 130

ranged in horizontal series, said series being spaced apart by distances equal to each other and equal to the distances separating said stringers, said standards being spaced apart by distances equal to the distances separating said posts, said stringers and the platforms proper of said sections projecting beyond the sections at each end thereof a distance equal to one half the distance separa-

ting said posts, and said sections being abut- 10
ted end to end.

In testimony whereof I affix my signature
in presence of two witnesses.

R. W. HAWES.
